UNITED STATES PATENT OFFICE.

CHARLES E. McMANUS, OF NEW YORK, N. Y.

BOTTLE CLOSURE.

Application filed July 6, 1922. Serial No. 573,177.

My invention relates to bottle closures, and more particularly to a type of closure commonly known as a crown cap, which ordinarily embodies a shell having a fluted 5 skirt and a cork cushion or disk within the shell against which the top of a bottle is adapted to be seated.

The type of bottle closure above referred to has been extensively used, the sealing or 10 cushioning disk having been made of natural cork and also of a so-called composition cork consisting of cork granules bonded together by means of a suitable binder, adhesive or glue. In such caps the sealing of 15 the top of a bottle is against the cork or cork composition disk and in the event of voids in the surface of said disk presented toward the contents of a bottle even though they may be comparatively small, gases with 20 which the beverage is charged, escape through the seal, developing what is known in the trade as "leakers".

The closure of my present invention is so constructed that a bottle will be sealed both 25 at the top of the mouth of the bottle and about the edges thereof, thus securing a double seal as a result of the compression of the material of the sealing or cushioning member, which has a rim or skirt of relatively greater thickness and resiliency than 30 the portion of said member which engages the top of the bottle. While the thickness of the sealing or cushioning member is material only in so far as it controls the 35 cost of the material entering into the closure, I preferably use a fairly thin material, since this permits economy in the production of the closure while affording a sufficiently tight seal to hold any pressure within bottles sealed by closures of this character. 40

Closures embodying my invention are capable of use with heavily charged beverages and after the application of the cap, bottles and their contents may be sterilized 45 if desired, without permitting the escape of gases as a result of the increased pressure developed during sterilization. Furthermore, sterilization cannot affect the binders, adhesives or glues used in assembling the 50 closure, since the compression of the skirt of the sealing or cushioning member will form a tight mechanical joint between same and the material of the shell which will effectively exclude moisture from between the 55 shell and the sealing or cushioning member.

In order to secure the desired thickness of both the top and the skirt of the sealing or cushioning member, I form this member of a laminated material, one lamina of which is of rubber or an insoluble rubber substitute, to impart the desired resiliency to the member, and another lamina of which, that presented towards the contents of a bottle, possesses flexibility and is non-absorbent, 60 so as to prevent the contents of the bottle from contacting with the resilient portion of the cap, which contact might impart to a beverage, the characteristic flavor of this resilient material. Furthermore the non-absorbent lamina above referred to, which 65 may be termed the facing lamina, presents a neat finish in the closure, and permits the desired formation of the skirt thereof, since it may be given a permanent form when 70 folded or bent under pressure.

A closure embodying my invention is adapted to be machine made by a continuous operation of the machine, thus avoiding re-handling of the closures during their manufacture. 75

The invention consists primarily in a bottle closure embodying therein a skirted shell adapted to be attached to a bottle, and a skirted laminated sealing member embodying therein a resilient lamina presented towards said shell and a substantially non-absorbent facing lamina presented towards the contents of a bottle, the skirt of said sealing member being relatively thicker than the top thereof, whereby the top of the bottle will be sealed against the top of said sealing member and the edge about the top of the bottle will be sealed against the skirted flange of said member; and in such other novel features of construction and combination of parts as are hereinafter set forth and described, and more particularly pointed out in the claims hereto appended. 85

Referring to the drawings, 90 Fig. 1 is a vertical section through a closure embodying my invention;

Figure 2 is a plan view of the inside of said closure; and

Fig. 3 is a view similar to Fig. 1 showing 95 a modified formation of the skirt of the sealing member.

Like letters refer to like parts throughout the several views.

In the embodiment of my invention shown 110 in the drawings, I employ a shell preferably of metal, although it may be made, if de-

sired, of other material, having an attaching portion of fluted edge *a*, a cylindrical portion *b* and a concaved top *c*.

Within the said shell is a sealing or cushioning member formed of laminated material and cupped to conform to the cylindrical portion *b* of the shell, thus presenting a top area *d* substantially coincident with that of the top *c* and adapted to be engaged by 10 the top of a bottle and to be exposed to the contents of a bottle through the top thereof; and a skirt *d'* of relatively greater thickness than said top and adapted to be compressed when the closure is being applied to the bottom, by engagement with the rounded bead about the top of a bottle.

That portion of the sealing or cushioning member which is presented toward the portions *b* and *c* of the shell consists of a thin 20 lamina *e* of soft vulcanized rubber, and that lamina indicated at *f* which is presented toward the contents of a bottle, consists of oil or wax treated paper which is sufficiently flexible to yield and take form under pressure while being substantially non-absorbent and substantially impermeable by gases contained within the bottle, thus constituting a 25 protecting facing for the cushioning or sealing member, which facing has a highly resilient backing, to facilitate the formation of a tight seal between same and the mouth of a bottle.

In assembling the closure, the laminated material is fed in relation to the shell in disk 35 form, suitable dies being used to first cup this material and then fold the edge thereof upon itself under sufficient pressure to give permanent form thereto, and double the thickness of the skirt *d'*. This increased 40 thickness gives the desired added resiliency about the edge of the top of a bottle, so as to ensure a tight seal at this point and compensate for variances in the dimensions of 45 different bottles, or possible imperfections therein. The treated paper facing *f*, if sufficient pressure be used, will overcome that elasticity inherent to the lamina *e* which otherwise would have a tendency to cause the folded edge to resume its normal cupped 50 position.

In the form of the invention shown in Figs. 1 and 2, the skirt *d'* is formed by rolling action of the edge of the material forming the sealing or cushioning member, while 55 in the form of the invention shown in Fig. 3, said skirt is formed by an angular bending action, so that the different thickness thereof will extend substantially parallel one with the other.

60 The permanency of the skirt *d'* results from the adaptability of fibrous material such as paper, to take form as a result of attenuation and compression of the fibers therein, compression being relied upon to impart 65 the desired circular form to the folded skirt,

and also to prevent a reflex action of the highly resilient lamina *e* of the sealing or cushioning member.

In actual practice, to secure the desired thickness of the cushioning or sealing member throughout, I preferably provide a lamina intermediate the laminae *e* and *f* and bonded thereto respectively, this intermediate lamina being shown at *g* in the drawings, and consisting preferably of untreated 70 paper having one face bonded to the lamina *e* by means of any suitable binder, adhesive or glue, and the other face bonded to the lamina *f* by a stratum of asphaltum or other suitable non-absorbent, flexible cement. 75

In assembling the closure, the lamina *e* is cemented to the top *c* of the shell by means of any desired, well known adhesive, such as copal adhesive, or adhesives containing albumen or casein, with or without 80 sodium silicate, the final assembling of the closures in a machine involving the steps of subjecting the binder, adhesive or glue to pressure applied through the cushioning or sealing member to the top and sides of the 85 shell and against a suitable heated plate for the purpose of eliminating the moisture in the adhesive, making it tacky and securing the desired intimate relation between the 90 two surfaces to be bonded together while 95 the binder, adhesive or glue is in this condition.

Closures embodying my invention are applied to bottles by means of an ordinary capping machine whereby a closure is placed 100 upon the neck of a bottle and forced thereon by means of a plunger, a sealing throat distorting the fluted skirt or other securing means, so as to clamp the cap about the neck of a bottle after the maximum pressure 105 has been applied to the top *c* of the closure.

In developing the pressure upon the top 110 of a closure, embodying my invention, the portion of the sealing or cushioning member which contacts with the facing lamina *f*, will distort said facing lamina, the intermediate lamina *g* and the resilient lamina *e*, or compress same sufficiently to form a gas 115 and liquid tight joint at the top of the bottle. At the same time the curvature of the bead about the top of the bottle will engage the skirt *d'* with the two fold result of a slight crushing action upon said skirt in the direction of the pressure, and a lateral compression thereof due to the curvature of the bead. These conditions will cause a slight 120 piling of the material of the skirt adjacent the portion *d* thereof and a sealing compression completely around the bead as well 125 as in the piled portion. As a result, any minor imperfections in the bead, or slight variances in the outside diameter thereof, will be compensated for, particularly as the increased thickness of the skirt *d'* will per-

mit a larger range of compression than could be secured by a single thickness of material.

The thickness of the various laminae is not material to the invention, the showing of the drawings, however, being somewhat exaggerated owing to the necessity for distinguishing the different laminae one from the other. The relative dimensions of the different parts of the closure may therefore vary widely from the showing of the drawings.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:—

1. A bottle closure embodying therein a skirted shell adapted to be attached to a bottle, and a skirted laminated sealing member embodying therein a resilient lamina presented towards said shell and a substantially non-absorbent facing lamina presented towards the contents of a bottle, the skirt of said sealing member being formed by folding the material of said sealing member upon itself, whereby said skirt will be relatively thicker than the top thereof, so that the top of the bottle will be sealed against the top of said sealing member and the edge about the top of the bottle will be sealed against the skirted flange of said member.
2. A bottle closure embodying therein a skirted shell adapted to be attached to a bottle, and a skirted laminated sealing member embodying therein a lamina of soft vulcanized rubber presented towards said shell and cemented thereto, a substantially non-absorbent facing lamina consisting of fibrous material impregnated with a moisture resisting substance, presented towards the contents of a bottle, and an intermediate lamina bonded to said facing lamina respectively, the skirt of said sealing member being relatively thicker than the top thereof, so that the top of the bottle will be sealed against the top of said sealing member and the edge about the top of the bottle will be sealed against the skirted flange of said member.

tively thicker than the top thereof, whereby the top of the bottle will be sealed against the top of said sealing member and the edge about the top of the bottle will be sealed against the skirted flange of said member.

3. A bottle closure embodying therein a skirted shell adapted to be attached to a bottle, and a skirted laminated sealing member embodying therein a lamina of soft vulcanized rubber presented towards said shell and cemented thereto, a substantially non-absorbent facing lamina consisting of fibrous material impregnated with a moisture resisting substance, presented towards the contents of a bottle, and an intermediate lamina bonded to said facing lamina by a flexible, moisture resisting adhesive, and to said resilient lamina, the skirt of said sealing member being relatively thicker than the top thereof, whereby the top of the bottle will be sealed against the top of said sealing member and the edge about the top of the bottle will be sealed against the skirted flange of said member.

4. A bottle closure embodying therein a skirted shell adapted to be attached to a bottle, and a skirted laminated sealing member embodying therein a lamina of soft vulcanized rubber presented towards said shell and cemented thereto, a substantially non-absorbent facing lamina consisting of fibrous material impregnated with a moisture resisting substance, presented towards the contents of a bottle, and an intermediate lamina bonded to said facing lamina by a flexible, moisture resisting adhesive, and to said resilient lamina, the skirt of said sealing member being formed by folding the material of said sealing member upon itself, whereby said skirt will be relatively thicker than the top thereof, so that the top of the bottle will be sealed against the top of said sealing member and the edge about the top of the bottle will be sealed against the skirted flange of said member.

In witness whereof I have hereunto affixed my signature this 23rd day of June, 1922.

CHARLES E. McMANUS.
